UNITED STATES PATENT OFFICE.

RAY P. FARRELL AND CLAUDE E. MOON, OF OXNARD, CALIFORNIA.

PILOT SIGNAL FOR ELECTRIC HEATING DEVICES.

1,425,462.

Specification of Letters Patent. Patented Aug. 8, 1922.

Application filed October 16, 1920. Serial No. 417,383.

To all whom it may concern:

Be it known that we, RAY P. FARRELL and CLAUDE E. MOON, citizens of the United States, residing at Oxnard, in the county of 5 Ventura and State of California, have invented certain new and useful Improvements in Pilot Signals for Electric Heating Devices, of which the following is a specification.

10 This invention relates to an improved pilot signal for electric heating devices and has as one of its principal objects to provide an arrangement whereby the fire hazard incident to the use of such devices will be materially reduced.

15 The invention has as a further object to provide an arrangement wherein the pilot signal will be energized as long as the circuit of the heating device is closed so that 20 the operator of the device cannot, at such time, likely forget and leave the circuit closed to cause overheating of the device with resultant fire.

25 And the invention has as a still further object to provide a signal employing a low voltage signal lamp and wherein the presence of the lamp upon the heating device will not affect the efficiency thereof.

30 Other and incidental objects will appear hereinafter.

In the drawings:

Figure 1 is a side elevation showing an electric iron embodying our improved signal.

35 Figure 2 is a horizontal sectional view more particularly illustrating the mounting of the transformer employed, and

40 Figure 3 is a fragmentary section showing the mounting of the guard for the signal lamp employed.

In the present instance, we have shown our improved pilot signal in connection with an electric iron. However, as will be better appreciated as the description proceeds, the 45 invention is well adapted for use in connection with other types of electric heating devices and we do not, therefore, wish to be limited in this regard. The base of the iron is indicated at 10 and fitting upon said base

50 is the usual cover 11. Projecting through said cover are the circuit posts 12, these posts being electrically connected in the ordinary manner with the heating element or coil of the iron. Upon the lower end portion of 55 each of the posts is threaded a pair of nuts 13. As will be at once appreciated, a socket

member, as suggested in dotted lines in Figure 1, is designed to be fitted over the posts for coupling the iron with a source of current, the coupling member being carried by 60 a suitable conductor. Mounted upon the cover of the iron is a handle bracket comprising arms 14 and 15 joined by a connecting portion 16 through which are engaged the usual cap screws securing the bracket in 65 position. In order that as little heat as possible may be transferred to the handle and the upper parts of the iron, bosses 37 are provided on top of the cover 11 and upon these bosses the handle portion 16 is made 70 to rest. Supported between the upper ends of said arms is a handle 17.

In carrying the invention into effect, we employ a transformer capable of changing the voltage from 110 to 4 or 6 volts, according to the size of pilot lamp used. This transformer is preferably enclosed in an oblong casing 18 shaped to fit between the lower end portions of the arms 14 and 15 of the handle bracket of the iron and provided at its lower side with cross ribs 19 abutting the connecting portions 16 of said bracket for spacing the casing upwardly therefrom in order to prevent too great a heat transmission from the iron to the casing of the 80 transformer. At its lower corners, the casing is formed with lateral ears 20 engaging the side edges of the bracket arms for holding the casing against lateral movement and upstanding from the casing at its upper side 85 are lugs 21 through which are engaged suitable cap screws threaded into the bracket arms for firmly securing the transformer in position. Suitably mounted in the forward 90 end portion of the casing 18 is a lamp socket 22 in circuit with the secondary coil 35 of the transformer and projecting through the bottom wall of the casing at its rear end portion are spaced spring contacts 23 in circuit with the primary coil 36 of the transformer. In this connection, it may be stated that the transformer may be of any preferred internal construction or placed in the handle or the body of the flat iron instead of in a special casing. Set into the bottom 100 wall of the casing is a dielectric block 24 insulating the spring contacts with respect to each other and, as will be best observed upon reference to Figure 1 of the drawings, the connecting portion 16 of the handle bracket 105 is provided at its rear end with an opening 110 receiving the contacts therethrough. Se-

cured between the pair of nuts 13 upon the terminal post 12 of the iron is a pair of forwardly projecting spring contacts 26 with which the contacts 23 coat.

- 5 At its lower end portion the arm 14 of the handle bracket is provided with a widened straight portion 27 and formed therethrough is, as particularly shown in Figure 3, an opening 28 having the lamp socket 22 registering therewith. Removably fitting through said opening to engage within the socket is a pilot lamp or signal 29 having the usual bayonet slot connection with the socket. Struck from a portion 27 15 of the arm above and below said opening are forwardly directed lugs 30 and held by said lugs to house the pilot lamp is a perforated guard cap 31. At its base, this cap is provided with an annular flange 32 and formed 20 in said flange are oppositely disposed notches 33 adapted to be brought into register with the lugs 30 so that the cap may be readily applied or removed, the lugs normally engaging over the flange for firmly holding 25 the cap in position.

As will now be readily understood in view of the preceding description, when the circuit through the heating element of the iron is closed, current will flow through the transformer for energizing the pilot lamp 29 so that a person using the iron will, as long as said circuit remains closed, always be apprised of the fact that the current through the iron is turned on. Liability of forgetting the iron when the current is so turned on will thus be greatly minimized and the liability of fire through accidental overheating of the iron accordingly reduced. The bulb of the lamp 29 may be colored red or 40 any other approved distinctive color so that when the lamp is energized the light therefrom will be readily noticeable. Further, attention is particularly directed to the fact that the presence of the pilot lamp upon the 45 iron will not detract from the heating of the heating element of the iron and will in no way affect the efficiency of the iron.

Having thus described the invention, what is claimed as new is:

- 50 1. In an electric iron, the combination of circuit posts with a heating element of the

iron, handle bracket arms carried by the iron, a transformer having primary and secondary windings, said primary winding being electrically connected with said posts, 55 a pilot lamp in circuit with the secondary winding of the transformer, a casing for said transformer adapted to fit between said arms, said casing having lugs engaging said arms and bolts for holding said arms and 60 casing together.

2. In an electric iron, the combination of circuit posts with a heating element of the iron, contacts carried by said posts, handle bracket arms carried by the iron in spaced 65 relation to the iron, a transformer having a primary and a secondary winding including contacts of the primary winding coacting with said first mentioned contacts, a casing for said transformer adapted to fit between said arms, said casing having lugs 70 engaging said arms and bolts for holding said arms and casing together, spacing ribs on the under side of said casing for preventing heat transmission from the iron to the 75 casing, a lamp socket carried by the casing in circuit with said secondary winding and a pilot lamp engaged in said socket.

3. In an electric iron, the combination of circuit posts with a heating element of the iron, contacts carried by said posts, handle bracket arms carried by the iron in spaced 80 relation to the iron, a transformer having a primary and a secondary winding including contacts of the primary winding coacting 85 with said first mentioned contacts, a casing for said transformer adapted to fit between said arms, said casing having lugs engaging said arms and bolts for holding said arms and casing together, spacing ribs on the un- 90 der side of said casing for preventing heat transmission from the iron to the casing, a lamp socket carried by the casing in circuit with said secondary winding and a pilot lamp engaged in said socket, a cap for said 95 lamp and means for rigidly holding said cap to one of said arms.

In testimony whereof we affix our signatures:

RAY P. FARRELL. [L. S.]
CLAUDE E. MOON. [L. S.]
